(74) Attorney, Agent, or Firm—Sheldon & Mak; Jeffrey G. Sheldon

(57) **CLAIM**

The ornamental design for seating, as shown and described.

DESCRIPTION

FIG. 1 is a perspective view of seating according to the present invention;

FIG. 2 is a reduced rear elevation view of the seating of FIG. 1;

FIG. 3 is a reduced side elevation of the seating of FIG. 1, taken on the right side of the seating, where the right side elevation view is a mirror image of the left side elevation view;

FIG. 4 is a reduced top plan view of the seating of FIG. 1; FIG. 5 is a reduced front elevation view of the seating of FIG. 1; and,

FIG. 6 is a reduced bottom plan view of the seating of FIG. 1.

Arm rests are shown as broken lines, and are present only for illustrative purposes and form no part of the claimed design of the invention.
